NOZZLE FOR SHOE CHANNEL CEMENTING
MACHINESWilbur L. MacKenzie, Beverly, Mass., assignor to
United Shoe Machinery Corporation, Paterson,
N. J., a corporation of New JerseyApplication October 1, 1935, Serial No. 43,064
In Great Britain September 25, 1935

25 Claims. (Cl. 91—43)

This invention relates to nozzles for machines for applying cement to the channels of shoe soles after the outseam has been formed, thereby to attach the channel flap to the sole. The invention 5 is herein illustrated as embodied in a machine of the extrusion type.

It is well understood in the manufacture of shoes that a seam for attaching the cutsole may be formed at the bottom of a channel cut in the 10 sole and that after the seam has been formed the channel flap may be cemented to the sole to hide the seam. Prior to the formation of the seam the channel flap is lifted to facilitate the sewing operation, this usually being done while 15 the sole is in temper, and as a result the flap is wrinkled transversely of its length, especially around the toe end of the sole. When the time comes for the application of cement to the channel, specifically to the channel base and the inside of the channel flap, the flap may be dry 20 and as a result quite stiff and hard. That being the case the under surface of the flap provides a wrinkled surface. Obviously, the contour and outline of the sole are both irregular. Coating shoe channels has commonly been performed by 25 means of a rotary brush. With the rubber cements ordinarily employed this sort of an apparatus is very successful. However, if the machine is to be used with cements of the pyroxylin type, or the polymerized chloroprene type, one 30 form of which is commonly known as Neoprene, then it is essential to avoid soiling the outside of the shoe because of the difficulty in removing such cements from the shoe upper, for example. It is, 35 furthermore, even more essential that exactly the desired quantity should be applied in order that there may be no squeeze-out when the channel flap is pressed into place.

Accordingly, an important object of the invention 40 is to provide an improved nozzle for a channel cementing machine of the extrusion type by means of which the cement may be applied expeditiously in just the desired quantities and without danger of soiling the adjacent parts of the shoe.

For a machine of this type a nozzle must be 45 employed which is adapted to enter the channel and to apply cement to the bed of the channel and to the inner face of the channel flap in substantially equal quantities. To this end, a feature 50 of the invention resides in an improved nozzle construction which, as illustrated, is V-shaped, is tapered to form a leading edge, and has an end face transverse to the length of the channel in 55 which is the outlet opening of a passage leading

through the nozzle. Cooperating with this end face to form lateral passages extending heightwise of the channel is a cover plate or deflector, a portion of which is brought into cement-tight engagement with the end face of the nozzle, and the remainder of which is spaced from the end face by reason of a cut-away portion which is illustrated as formed in the cover plate, thus providing a shoulder which determines the end of each of the lateral passages.

Still another feature of the invention resides in a novel construction greatly facilitating the even distribution of cement through the two lateral passages which deliver cement to the flap and the channel bed, by equalizing the frictional 10 resistance of the outflowing cement. To this end, the end face of the nozzle in the illustrated construction is recessed, leaving marginal portions of uniform width adjacent to the edges of the end face.

When applying cement of the polymerized chloroprene type there is a tendency for the cement to be repelled by the leather. This is overcome, in accordance with still another feature of the invention, by the provision of duplicate sets of 15 lateral passages by means of a pair of superposed cover plates, the intermediate one of which is apertured to provide communication between the two sets of passages. As a result of this construction the cement extruded through the first 20 set of passages is effective to wet the leather and this greatly facilitates the application thereon of a coating of cement of the desired thickness.

Other features of the invention relating to the structure of the machine are not claimed herein 25 since they form the subject matter of a divisional application Serial No. 111,453, filed Nov. 18, 1936.

These and other features of the invention will be described in the following specification taken 30 in connection with the accompanying drawings, 35 in which

Fig. 1 is an angular view of the nozzle and associated operating tools, showing the presentation of a piece of work to the machine;

Fig. 2 is an angular view on a much larger 45 scale of a nozzle, with a cover plate removed;

Fig. 3 is a similar view of a modified construction in which two plates are employed;

Fig. 4 is a side elevation of the nozzle shown in 50 Fig. 2, with the cover plate in position;

Fig. 5 is a side elevation of the nozzle shown in Fig. 3 with the plates in position;

Fig. 6 shows a modified form of the nozzle of 55 Fig. 2;

Fig. 7 is an elevation looking at the leading edge of the nozzle shown in Fig. 6; and

Fig. 8 is a plan view of a fragment of a shoe sole, showing the flap in lifted position, and illustrating the application of cement by means of a nozzle such as that shown in Fig. 5, the end portion of which is shown in a section taken on the line VIII—VIII of Fig. 5.

In the embodiment illustrated in the drawings, a machine supports a cement receptacle (not shown) from which cement is extruded under pressure through a nozzle 20 by which it is applied to the work. A piece of work, such as a shoe 22 mounted on a last, has an outsole attached by stitches positioned at the apex or bottom of a channel cut in the sole. In the cutting of this channel, there is formed a channel flap 26 which is to be cemented to the bed 28 of the channel in the position which it occupied before the channeling cut was made. The shoe is moved progressively past the nozzle 20 to cause the treatment of successive portions of the channel flap and the channel bed. Control of the quantity of cement extruded may be effected in any desired way.

In the machine, a nozzle carrier 42 is split at its upper end and held in the desired position on a rod 40 by pinch screws 46 (Fig. 1). A nozzle stem 51 has a flange 48 which is supported on spaced flanges 50 formed upon the carrier 42 and to which it is bolted. The connection between the flexible tube 18 and the nozzle stem 51 comprises a fitting 52 which contains a turn valve 54 and is provided with a base 56 secured in tight relation to the flange 48 of the nozzle stem 51 by screws (not shown). The upper end of the fitting is threaded in a T fitting 58 through which cement is supplied to the nozzle 20, the latter having a flange 55 and a nipple 57. This nipple is received in a socket in the lower end of the stem 51 which has a flange 53 held to the flange 51 by screws.

Provision is made for feeding the work by means of a rubber-tired roll 60, the flap 26 being pressed against the side of the nozzle 20 by means of an oscillated flap-pressing finger 82 clamped in the lower arm of the bell crank lever 84 which is pivotally supported by depending arms 86 secured to the nozzle carrier block 42. A vibratory motion is imparted to the finger 82 by means of a horizontal rod 88.

The nozzle 20 is positioned in the machine as shown in Fig. 1 in depending position and is inclined downwardly and forwardly with respect to the direction of movement of work presented thereto so that a removable plate 1180 secured to the outlet face of the nozzle lies approximately in a vertical plane passing through the axis of the feed roll. The lower end 60 of the nozzle is tapered heightwise at 182 (Fig. 3) to aid in pushing it into the channel and has a comparatively sharp leading edge 184 (Fig. 8) in which there is an outlet 186 (Figs. 2, 3 and 4) to deliver cement at the bottom or root of the channel. This leading edge is formed by the intersection of two lateral surfaces, one of which, a plane surface 214, is substantially parallel to the axis of the nozzle. This cement also lubricates the nozzle, as it were, making it easier to feed the work. The nozzle also has a substantially triangular end surface 188 through which, at 192, emerges an outlet passage 190 extending down through the nozzle to supply cement to the delivery end thereof. The outlet 186 communicates with the passage 190 through a

branch passage 187. It is through this passage 190 that cement is pumped at substantially constant pressure when the valve 54 is opened. As shown in Fig. 3, the shoe is moved away from the operator so that it approaches the leading edge 184 of the nozzle and so that the face 188 and the cover or deflector plate 1180 are upon the trailing face of the nozzle.

It is desired, then, to cause the cement to be applied uniformly upon both the channel flap 26 and the channel bed 28 as well as in the bottom of the channel. To this end, the cover plate 1180 (Fig. 2), corresponding to the plate 1180 and positioned directly to overlie the outlet opening 192 of the passage 190, acts as a deflector and cooperates with the face 188 to provide a transverse slot 194 (Fig. 4) forming delivery passages or slots extending from the apex of the tapered end of the nozzle heightwise thereof to a point determined by a shoulder 196 on the cover plate. A series of cover plates having this shoulder positioned at various distances from the pointed lower end may be utilized for channels $\frac{1}{4}$ -inch, $\frac{5}{16}$ -inch or $\frac{3}{8}$ -inch wide. Such nozzles, with their narrow outlet slots, show a notable flexibility in their ability to coat properly with channels, the depth of which varies between different parts of a shoe. Thus, even if the slot is longer than the channel is deep, the cement, due to its cohesiveness, will draw down from the upper end of the slot to the upper edge of the work being coated without being extruded over the edge of the channel flap or the channel base, as the case may be. Were a series of holes employed instead of a slot, the cement extruded from the exposed upper holes would be forced over the edge of the channel flap or the channel base. The cover plate is also provided with an undercut shoulder 198 which is intended to rest upon an undercut shoulder 200 (Figs. 2 and 4) formed upon the nozzle thereby to assist in locating the cover plate in exact relation to the triangular face 188 of the nozzle. The area 197 between the two shoulders fits closely against the end face 188. The outline of the triangular portion of the cover plate is slightly smaller than the corresponding outline of the face 188 to avoid any tendency of the edges of the cover plate to scrape off the cement just applied. These edges act as a sort of spatula to smooth out the applied coating. Further to assist in locating the cover plate upon the nozzle, there may be provided a pin 202 which is received in a socket 204 in the nozzle. The cover plate will be held in position by a screw 206 having a threaded stem 210. The elliptical opening 192 formed where the passage 190 intersects and emerges in the face 188 is joined to the apex of the tool by means of a shallow groove 212 thereby insuring delivery of a sufficient quantity of cement to the bottom of the channel.

When the nozzle is in position in the machine, the channel flap 26 will be pressed against the plane surface 214 whereas the bed of the channel will be held against the opposite surface of the nozzle terminating in the edge 216. Under some conditions, the bed 28 of the channel will not be flat but will be curved away from the plane of the bottom of the sole toward the shoe upper. This will be found in women's close-edged shoes and may result in a different curvature of the channel bed around the forepart than that which is in the shank. In order to adapt the nozzle for best operation with a close-edged shoe, it is found desirable to change the nozzle construction to

that shown in Figs. 6 and 7 where parts similar to those shown in Fig. 2 have been given similar numerals to which 1000 has been added. This nozzle differs from that shown in Fig. 2 in having 5 an inner or back lateral surface which is curved inwardly to form a concave portion or valley terminating in the curved edge 220 which will be close to the shape of the channel bed around the forepart of the shoe and will approximate that 10 found in the shank of the shoe. With this construction, the cover plate 1180 is also provided with a pointed end having a curved edge 222. It will be noted that the shoulder 1196 in the 15 cover plate provided for this style of nozzle is not exactly parallel to the shoulder 1198 but deviates from that relation in accordance with the need for providing outlet passages which will coact with the widths of the channel flap and the channel bed.

20 In constructing nozzles of the type shown in Fig. 2, it is common to do some hand filing where the groove 212 joins the elliptical outlet opening 192 and sometimes this is done carelessly, bringing the opening nearer to one side edge than the other. This renders unequal the frictional resistance offered to the cement flowing to the two sides and results in a somewhat uneven distribution of cement upon the two sides of the channel. It is avoided by forming a recess 224 (Figs. 3 and 30 6) in the end face of the nozzle which is separated from the edge of the nozzle by a ledge 226 of uniform width, thus insuring an even distribution of cement. In the form shown in Fig. 6, this recess is joined to the tip of the nozzle by a 35 groove 228 corresponding to the groove 212 in Fig. 3.

When the nozzle is to be employed for cements of the polymerized chloroprene type, one form of which is marketed under the name Neoprene, then a nozzle construction such as that shown in Figs. 3 and 5 may be advantageously employed and has a pair of cover plates or deflectors 230 and 232. These deflectors, which are kept in alignment with one another by means of a stud 234 entering a socket 236, are mounted for slight lateral movement around a cylindrical portion 268 on the screw 206. To this end, the shoulder 240 on the inner plate 230 is spaced slightly from the shoulder 200 on the nozzle. The intermediate plate 230, having a surface 241 in close contact with the end surface of the nozzle, is also provided with a shoulder 242 corresponding to the shoulder 196 and, when positioned in cement-tight relation to the end face 188, forms a transverse slot 249 terminating in lateral passages through which the cement is extruded upon the channel flap and the channel bed. This intermediate plate is also provided with an elongated opening 244 opposite the outlet end of the passage 190 (Fig. 8) so that a portion of the cement passes directly to the slot 251 (Figs. 5 and 8) between the lower portion of the intermediate plate 230 and the face of the outer plate 232. This slot is limited by a shoulder 246 upon the forward face of the plate 230. Thus, two slots are formed providing two lateral passages upon each face of the nozzle, these being separated by the thin lower end 248 of the intermediate plate 230. The edges of the lower end 248 are serrated 55 at 250 thereby to provide a sort of spreading action for the cement which is delivered to the work from the slot 249. The generally triangular lower end 248 of the intermediate plate is slightly smaller than the corresponding portion of the 60 nozzle, while the outline of the lower end 252 of

the cover plate 232 is even smaller and is rounded on the outer edges. This, together with the opportunity for slight lateral displacement of the lower ends of the two cover plates with respect to the nozzle, reduces any interference between the 5 nozzle and the shoe to a minimum as the nozzle treats sharply curved portions of the channel. The cement extruded through the first slot 249 is effective to wet the surface of the leather of the channel flap and channel bed while that extruded through the second slot 251 is enabled thereby to stick even more readily to these already coated surfaces, and to be applied in uniform and pre-determined quantities.

Having thus described my invention, what I 15 claim as new and desire to secure by Letters Patent of the United States is:

1. In a channel cementing machine, an extruding nozzle having a tapered end to facilitate its insertion in the channel of a shoe and past which the shoe is moved to coat the linear extent of the channel, said nozzle being also tapered toward that side which is leading with respect to the direction of movement of the work and being provided with an outlet passage terminating approximately at the apex of the tapered portion on the leading side of the nozzle and being also provided with lateral slots to the rear of said passage and extending from the apex of the nozzle up the sides of the nozzle to facilitate the application of cement to the bed and the flap of the channel.

2. In a channel cementing machine, a tapered nozzle having a face provided with a recess, the edges of which are substantially equidistant from the sides of the nozzle, thus forming lateral ledges of substantially uniform width, an outlet passage terminating within said recess, and a cover member overlying said recessed face and spaced from the ledges thereby to provide lateral passages 35 through which cement will be extruded in equal volumes.

3. In a channel cementing machine, a tapered nozzle for insertion in a shoe channel having a bed and a flap, said nozzle having a face provided with a recess, an outlet passage terminating within said recess, the margin of said recess at substantially the apex of the nozzle being provided with a groove, providing an enlarged passage for the delivery of cement to the very root of the 50 channel and a cover member overlying said recessed face and spaced from the unrecessed portion of the face of the nozzle, thereby to provide lateral passages through which cement will be extruded in equal volumes on the bed and flap of 55 the channel.

4. In a channel cementing machine, a nozzle having an end portion adapted to be inserted in the channel of a shoe and past which the shoe is moved to coat the linear extent of the channel, 60 said nozzle being tapered axially and toward that face of the nozzle which is leading with respect to the direction of movement of the shoe, thereby providing an edge on this leading face, said nozzle having an end face, an outlet passage through said nozzle terminating in said end face, said end face being also provided with a groove extending from the outlet of said passage to the apex of the nozzle, an auxiliary passage extending from said outlet passage to an opening in the 65 leading edge, and a cover member overlying the end face and spaced therefrom to provide lateral passages for coating the flap and the bed of the channel.

5. In a channel cementing machine, a nozzle 75

provided with a substantially V-shaped end face adapted to be positioned transversely of the length of the channel, said nozzle having an outlet passage intersecting said end face, a removable cover overlying said outlet opening and having its work-engaging portion substantially V-shaped, a portion only of said cover being spaced from said end face and another portion contacting with said face, thereby to define lateral outlet passages, and coacting undercut shoulders on the end face of the cover for locating said cover in alignment with said end face.

6. In a channel cementing machine, a nozzle having an end face, an outlet passage terminating in said end face, a cover member spaced from the nozzle and provided with a flat inner surface, and an apertured intermediate deflector the work-engaging end of which is provided with shoulders upon each surface, thereby together with faces of said nozzle and said cover to define two sets of lateral passages through which cement may be delivered to the channel flap and the channel bed.

7. In a channel cementing machine, a nozzle having a tapered outlet end, said nozzle being supported in depending position and inclined downwardly and forwardly with respect to the direction of movement of work presented thereto, said nozzle having a curved, sharp leading edge to help to open the channel and a substantially V-shaped trailing face, an outlet passage terminating in said trailing face, and a cover plate overlying said outlet and coacting with the face to provide lateral passages extending heightwise substantially in normal relation to the length of the channel in a shoe presented thereto.

8. In a channel cementing machine, a tapered nozzle adapted to be inserted in the channel of a shoe sole and shaped substantially to fit the channel, said nozzle being provided with outlet slots formed in the lateral surfaces of said nozzle for the delivery of cement to the channel flap and the channel bed resting against said surfaces, respectively, one of said lateral surfaces being curved thereby better to contact with the channel bed and the other lateral surface being parallel to a longitudinal axis of the nozzle.

9. In a channel cementing machine, a tapered nozzle adapted to be inserted in the channel of a shoe sole and having a lateral surface touching the channel bed and curved to approximate the transverse curvature of the channel bed and a flat lateral surface against which the channel flap is pressed, said nozzle being provided with an outlet passage formed in said curved lateral surface for the delivery of cement directly to the similarly shaped channel bed, said lateral surfaces intersecting to form a thin leading edge.

10. In a channel cementing machine, a tapered nozzle having a face transverse to the length of the nozzle and an outlet passage terminating at a mid portion of said face, one side of said nozzle being substantially straight to cooperate with the flap of a shoe sole and the other side of said nozzle being concave to cooperate with the curved bed of the channel of a shoe sole, and a deflector plate overlying the end of said face and shaped like the nozzle to cooperate therewith in providing lateral passages, one of which will be straight and the other curved.

11. In a channel cementing machine, a tapered nozzle adapted to be inserted in the channel of a shoe sole, said nozzle having on its trailing side a face lying transverse to the length of the channel, said nozzle having an outlet passage terminating

in said transverse face, and a deflector overlying said face and spaced therefrom to provide lateral passages, said deflector having serrated edges.

12. In a channel cementing machine, a nozzle having a tapered end portion and provided with a face transverse to the length of the nozzle, said nozzle having an outlet passage terminating in said face, an apertured deflector overlying said outlet opening and cooperating with said transverse face to provide lateral passages through which cement may be extruded upon the bed and flap of the channel, and another deflector overlying the apertured deflector and spaced therefrom to provide another set of lateral passages cooperating with the bed and the channel. 15

13. In a channel cementing machine, a nozzle having a tapered end portion and provided with a face transverse to the length of the nozzle, said nozzle having an outlet passage terminating in said face, an apertured deflector overlying said outlet opening and cooperating with said transverse face to provide lateral passages through which cement may be extruded upon the bed and flap of the channel, and another deflector overlying the apertured deflector and spaced therefrom to provide another set of lateral passages cooperating with the bed and the channel, said first named deflector having serrated edges. 25

14. In a channel cementing machine, a tapered nozzle having a transverse face provided with an outlet opening, and coacting defectors spaced from one another and from said transverse face, the intermediate deflector being apertured and having a serrated edge which is substantially co-extensive with the transverse face of the nozzle. 35

15. In a channel cementing machine, a tapered nozzle having a transverse face provided with an outlet opening, and coacting defectors spaced from one another and from said transverse face, the intermediate deflector being apertured and having a serrated edge which is substantially co-extensive with the transverse face of the nozzle, said other deflector being smaller than the serrated deflector thereby to avoid interference with the work as the curved portions of the channel are treated. 40

16. In a channel cementing machine, a nozzle adapted to be inserted in the channel of a shoe sole and past which the sole may be moved to coat successive portions of the channel, said nozzle being provided with a cover member cooperating therewith and spaced therefrom to provide lateral passages through which cement is delivered to the channel flap and the channel bed, said cover member being mounted for lateral self-adjusting movement thereby to accommodate the nozzle to curved portions of the channel. 55

17. In a channel cementing machine, a tapered nozzle adapted to be inserted in the channel of a shoe sole and past which the sole may be moved to coat successive portions of the channel, said nozzle having an end face and an outlet passage terminating in said face, and means providing a surface substantially parallel to said end face and cooperating therewith to provide a lateral passage, said means being mounted for a movement of self-adjustment with respect to the nozzle while maintaining its cooperating surface substantially parallel to the end face of the nozzle. 60

18. In a channel cementing machine, a tapered nozzle having an end face transverse to the length of the nozzle and provided with an outlet passage terminating in said face, and a deflector secured to said nozzle to overlie said face and to be spaced therefrom to provide lateral pas- 75

sages heightwise of the channel, said deflector being loosely mounted to provide for lateral twisting of the deflector by pressure of the work without substantially changing the size of the outlet lateral passages.

- 5 19. In a channel cementing machine, a tapered nozzle having an end face transverse to the length of the nozzle and provided with an outlet passage terminating in said face, and a deflector 10
10 cured to said nozzle to overlie said face and to be spaced therefrom to provide lateral passages heightwise of the channel, said deflector being loosely mounted to provide for lateral twisting of the deflector by pressure of the work without 15
15 substantially changing the size of the outlet lateral passages, said end face and the inner side of said deflector being provided with coating shoulders, thereby to limit the twisting movement of the deflector.
- 20 20. In a channel cementing machine, an extruding nozzle having an end portion adapted to be inserted in the channel of a shoe and past which the shoe is moved to coat the linear extent of the channel, said nozzle being tapered on its 25 leading side to help to open the channel and having on its trailing side a face substantially normal to the length of the channel and provided with a recess, a passage for the delivery of cement to said recess, and a removable cover plate associated with the nozzle overlying the recess and spaced from the unrecessed portion on the face of the nozzle along at least one side of the nozzle thereby to provide a lateral passage through which cement may be extruded for coating one 35 side of the channel.

21. In a channel cementing machine, a nozzle the end portion of which is adapted to be inserted in the channel, said nozzle being provided with an end face lying transversely of the channel 40 and having an outlet passage delivering to said end face, and a removable cover overlying said outlet passage and provided with a shouldered surface one portion of which is brought into close engagement with the end face of the nozzle 45 and the other portion of which is spaced from said end face thereby to provide a lateral passage for coating at least one side of the channel, said shoulder on the cover defining the upper limit of said passage.

- 50 22. In a channel cementing machine, a nozzle adapted to be inserted in the channel of a shoe

sole, said nozzle having a concave surface for reception of and contact with the base bed of the channel, a removable cover plate having a correspondingly curved edge, one of said parts being cut away along the concave surface to provide a curved delivery slot through which cement may be extruded to coat the channel bed, and an outlet passage within the nozzle leading to said cut-away portion.

23. In a channel-cementing machine, an acutely tapered nozzle provided with an end surface adapted to be positioned substantially normal to the length of the channel, said nozzle having an outlet passage intersecting said end surface, and a removable cover having a surface resting tightly against said end surface over one area and spaced therefrom over another area thereby to form a continuance of the outlet passage which terminates in a delivery opening, one of said coating surfaces being provided with a shoulder extending transversely of the axis of the nozzle thereby to define an upper limit of the delivery opening between the cover and said end surface along a side of the nozzle adjacent to one side of the channel.

24. In a cementing machine for shoe parts, an extruding nozzle between which and a shoe part relative movement is set up thereby to apply a coating in an elongated stripe along the shoe part, said nozzle being provided with a plurality of outlet slots extending transversely to the direction of relative movement and located behind one another with respect to said direction whereby cement extruded through the first slot is effective to wet the surface of the shoe part and cement extruded through the second slot applies a superposed coating of the desired thickness.

25. In a channel-cementing machine, an acutely tapered nozzle provided with an end face adapted to be positioned substantially normal to the length of the channel, said nozzle having an outlet passage delivering to said end face and a removable cover coacting with said end face to determine the direction of flow of cement from said outlet passage, said cover being spaced from the end face along an edge to provide a delivery opening substantially coextensive with one side of the channel, and means for clamping said cover on said nozzle.

WILBUR L. MACKENZIE. 50

CERTIFICATE OF CORRECTION.

Patent No. 2,098,347.

November 9, 1937.

WILBUR L. MacKENZIE.

It is hereby certified that error appears in the printed specification of the above numbered patent requiring correction as follows: Page 2, second column, line 17, before the word "delivery" insert lateral; page 3, first column, line 65, for "forward" read rear. The claims now appearing in the patent as numbers 20, 2, 3, 4, 21, 23, 5, 6, 7, 8, 22, 9, 10, 11, 24, 12, 13, 14, 15, 16, 17, 18, and 19, should bear the numbers 2, 3, 4, 5, 6, 7, 8, 9, 10, 11, 12, 13, 14, 15, 16, 17, 18, 19, 20, 21, 22, 23, and 24 respectively; and that the said Letters Patent should be read with these corrections therein that the same may conform to the record of the case in the Patent Office.

Signed and sealed this 8th day of February, A. D. 1938.

Henry Van Arsdale,
Acting Commissioner of Patents.
